(57) **CLAIM**

The ornamental design for a tumbler, as shown and described.

DESCRIPTION

FIG. 1 is a top, perspective view of a tumbler having a lid opening in a closed configuration.

FIG. 2 is a front elevation view of the tumbler thereof.

FIG. 3 is a rear elevation view of the tumbler thereof.

FIG. 4 is a left side elevation view of the tumbler thereof.

FIG. 5 is a right side elevation view of the tumbler thereof.

FIG. 6 is a top plan view of the tumbler thereof.

FIG. 7 is a bottom plan view of the tumbler thereof.

FIG. 8 is a top, perspective view of a tumbler having a lid opening in an open position.

FIG. 9 is a front elevation view of the tumbler thereof.

FIG. 10 is a rear elevation view of the tumbler thereof.

FIG. 11 is a left side elevation view of the tumbler thereof.

FIG. 12 is a right side elevation view of the tumbler thereof.

FIG. 13 is a top plan view of the tumbler thereof; and,

FIG. 14 is a bottom plan view of the tumbler thereof.

Broken lines shown are for illustrative purposes and form no part of the claimed design.

1 Claim, 12 Drawing Sheets
